STRAIGHT BAR KNITTING MACHINE AND A
METHOD OF OPERATING SAMEFritz Lambach, Tenafly, N. J., assignor to Robert
Reiner, Inc., Weehawken, N. J.

Application February 3, 1948, Serial No. 6,063

38 Claims. (Cl. 66—89)

1

This invention relates to textile machines, and more particularly to straight bar knitting machines.

An object of the present invention is to provide a straight bar knitting machine with a mechanism, by means of which loop transfer means for transferring loops from knitting needle to knitting needle of the knitting machine, such as a picot bar or lace fingers, may be moved automatically from a position out of cooperative relation to needles of the knitting machine into a position in cooperative relation to needles of the knitting machine and vice versa.

A further object of the present invention is to improve upon the construction of straight bar knitting machines as now ordinarily made.

Further objects and advantages of the present invention will be apparent from the following disclosure of an embodiment thereof. In the accompanying drawings:

Fig. 1 is a fragmentary front elevational view of a two-section straight-bar knitting machine, some parts being broken away, some parts being omitted for a better illustration of the invention.

Fig. 2 is a fragmentary side elevational view seen in the direction of the arrows 2 of Fig. 1, some parts being omitted and some parts being broken away for a better illustration of the invention.

Fig. 3 is a fragmentary sectional view taken along line 3—3 of Fig. 2.

Fig. 4 is a fragmentary sectional view taken along line 4—4 of Fig. 2.

Fig. 5 is a sectional view taken along line 5—5 of Fig. 1, some parts being broken away.

Fig. 6 is a sectional view taken along line 6—6 of Fig. 1.

Fig. 7 is a sectional view taken along line 7—7 of Fig. 6.

Fig. 8 is a fragmentary sectional view taken along line 8—8 of Fig. 6.

Fig. 9 is a sectional view taken along line 9—9 of Fig. 8.

Fig. 10 is a front elevational view of the actuating drive of the narrowing machine.

Figs. 11 and 11A when placed end to end from left to right in the order given make up a front elevational view of a picot bar and a portion of its actuating mechanism.

Fig. 12 is a sectional view taken on line 12—12 of Fig. 11A.

Fig. 13 is a sectional view taken on line 13—13 of Fig. 12.

Fig. 14 is a front elevational view similar to that shown in Fig. 11A, wherein, however, the

2

picot bar and its actuating mechanism are in a different position.

Fig. 15 is an exploded perspective view of the ratchet wheel mechanism forming a part of the actuating mechanism of the picot bar,

Fig. 16 is a sectional view similar to that shown in Fig. 6, wherein, however, the selecting mechanism of the picot bar actuating mechanism is in a different position, and

10 Figs. 17—19 are fragmentary views illustrating various positions of the elements of the actuating mechanism of the picot bar.

The drawings illustrate only those parts of a straight bar knitting machine, which are necessary for the understanding of the invention.

Referring now to Figs. 1, 2, and 5, 30 generally indicates the frame of a two-section straight bar knitting machine. A motor 32 mounted on a bracket 34 carried by the frame 30 of the knitting

20 machine is connected through a train of gears 36 with the main cam shaft 38 rotatably arranged in suitable bearings of the frame of the machine.

40 generally indicates a pattern chain carrying a series of buttons 42 for the control of certain mechanisms of the knitting machine. During the operation of the machine, the pattern chain is intermittently advanced in a manner known per se by any suitable mechanism. For example, a pattern chain cam 44 (see Figs. 1 and 5) keyed to the main cam shaft actuates a spring-loaded double-armed lever 46 which, in turn, actuates a double-armed lever 48 carrying a pawl 50 arranged for engagement with teeth of a ratchet wheel 52 connected to a rotatable drum 54 engaged with the pattern chain 40.

45 Each row of buttons 42 mounted on the pattern chain 40 in a predetermined manner is arranged for cooperation with a swingable spring-loaded jack of a series of jacks 56a, 56b . . . 56n mounted on a shaft 58 (see Figs. 1, 2, 3, and 5). Each jack is connected through wires, levers and rods with a controlling mechanism of the knitting machine. The drawings illustrate only the connections of the jacks 56c, 56e, and

50 56n. Obviously, each time when a button 42 comes into engagement with a projection of one of the jacks 56a, 56b . . . 56n, such a jack is swung about the shaft 58 against the action of the spring associated with such a jack. The swinging of a jack about the shaft 58, in turn, causes an actuation of a controlling mechanism connected with the jack through wires, levers and/or rods.

For example, as best shown in Figs. 1, 2 and 3, the wire 60 leading from the jack 56c is slid-

ably engaged with a bore arranged in the lower end of a lever 62, the upper end of which is secured to one end of a rod 64 journalled in bearings of brackets 66 secured to the frame 30 of the machine. A spring 68 (see Figs. 1 and 3) is interposed between the lower end of the lever 62 and a first set collar 70 secured to the rod 60. A second set collar 72 is secured to the free end of the wire 60, so as to serve as an abutment for the spring-loaded lower end of the lever 62. The lever 62 has a hook-like projection 74, which may be engaged by a swingable hook-like locking element 76 in a manner to be described hereinafter. When the hook-like locking element 76 and the hook-like projection 74 of the lever 72 are disengaged from each other as shown in full lines in Fig. 3, a rocking of the jack 56c by a button 42 of the pattern chain 40 from its normal position into the position shown in Fig. 3 will cause a swinging movement of the lever 62 from the dash-and-dot-line position of Fig. 3 into the full-line position of said Fig. 3 through the medium of the wire 60, set collar 70 and spring 68. If, however, in a manner to be described hereinafter, the hook-like locking element 76 and hook-like projection 74 are engaged with each other as shown in dash-and-dot lines in Fig. 3, a rocking of the jack 56c by a button 42 of the pattern chain 40 will merely cause a sliding movement of the wire 60 in the bore of the lever 62 against the action of the spring 68. As best shown in Figs. 1 and 2, the other end of the rod 64 is rigidly connected with the lower end of a lever 78, the upper end of which is connected by a wire 80 (see Figs. 2 and 4) with one arm 82 of a controlling element 84 swingably mounted on a pivot 86 projecting upwardly from the base 88 of a block 90 being substantially of U-shaped cross-section. Said block 90 swingably mounted on a shaft 92 carries an adjustable stop screw 94 capable of co-operation with a shaft 96 of the machine. A spring 98 stretched between a downward extension 100 of said block 90 and a stationary point of the machine tends to urge said stop screw 94 against said shaft 96, whereby the block 90 is held in a substantially horizontal position. Furthermore, a double-armed spring-loaded follower 102 carrying a roller 104 cooperating with a carrier-narrowing-spindle-cam 106 keyed to the main cam shaft 38 is swingably mounted on the shaft 92 between the side walls 108 and 110 of the U-shaped block 90. During the operation of the machine, the arm 112 of the follower 102 may freely rock within the U-shaped block 90, held in its position by the spring 98, in accordance with the shape of the carrier-narrowing-spindle-cam 106 engaged with the roller 104 of the follower 102, as long as the controlling element 84 is in the inactive position shown in Fig. 4. As soon as, however, upon an actuation of the jack 56c and a rocking movement of the lever 62, said controlling element 84 is swung about its pivot 86 into such a position, that its upward extension 114 (see Figs. 2 and 4) is below an abutment 116 arranged on the arm 112 of the follower 102, the next downward rocking of the arm 112 of the follower 102 caused by a rise on the carrier-narrowing-spindle-cam 106, causes a swinging of the block 90 against the action of the spring 98 in counter-clockwise direction. Now, the block 90 follows the reciprocating rocking movements of the arm 112 of the follower 102, as long as the controlling element 84 remains in

the active position with its upward extension 114 below the abutment 116 of the arm 112. As soon as the jack 56c controlled by the pattern chain 40 causes a return of the controlling element 84 into the inactive position shown in Fig. 4, the arm 112 of the follower 102 will again rock freely within the block 90 held in its inactive horizontal position by the spring 98, without causing a rocking of said block 90.

The lower end of a forward-racking connecting rod 118 is pivotally connected with an extension of the wall 108 of the block 90 at 120. The upper end of said forward-racking connecting rod 118 is pivotally connected at 122 with a three-armed lever 124 swingably but axially immovably mounted on a carrier spindle 126 rotatably arranged in the frame of the machine. The lever 124 carries a pawl 128 arranged for engagement with teeth of a ratchet wheel 130 keyed to the carrier spindle 126 for an intermittent controlled forward-racking of the carrier spindle nuts (not shown in the drawings). Furthermore, one end of a connecting rod 132 is pivotally connected to the three-armed lever 124 at 134, the other end of said connecting rod 132 is pivoted at 136 to a lever 138 swingably but axially immovably mounted on a narrowing spindle 140 journalled in suitable bearings of the frame of the machine. Said lever 138 carries a pawl 142 arranged for engagement with teeth of a ratchet wheel 144 keyed to the narrowing spindle 140 so as to cause a controlled intermittent forward-racking or movement towards each other of narrowing spindle nuts 146L, 146R engaged with a left-hand threaded portion and right-hand threaded portion respectively of the narrowing spindle 140 (see Figs. 1 and 5).

Furthermore, as best shown in Figs. 2 and 4, the lower end of a back-racking connecting rod 148 is pivoted to an extension of the wall 110 of the block 90 at 150. The upper end of said back-racking connecting rod 148 is pivoted at 152 to a three-armed lever 154 swingably but axially immovably mounted on the carrier spindle 126. Said rockable lever 154 carried a pawl 156 arranged for engagement with teeth of a ratchet wheel 158 (see Fig. 1) so as to cause a controlled intermittent back-racking of the carrier spindle nuts. One end of a connecting rod 160 (see Fig. 2) is pivotally connected to an arm of said rockable lever 154 at 162. The other end of said connecting rod 160 is pivoted at 164 to a three-armed lever 166 swingably but axially immovably mounted on the narrowing spindle 140. Said rockable lever 166 carries a pawl 168 arranged for engagement with teeth of a ratchet wheel 170 (see Fig. 1) keyed to the narrowing spindle 140 so as to cause a controlled intermittent back-racking or movement away from each other of the narrowing spindle nuts 146L and 146R.

The operation of the pawls 128 and 156 (see Fig. 2) causing the forward-racking and the back-racking of the carrier spindle nuts engaged with the carrier spindle 126 is controlled by a selecting control disc 172 rotatably arranged on the carrier spindle 126 and connected through the medium of a Bowden wire 174 to a spring-loaded cam follower 176 (Fig. 2) swingably mounted on a shaft 178. Said cam follower 176 cooperates with a controlling cam 180 of a series of controlling cams keyed to a control shaft 182 (see Figs. 1 and 5) automatically actuated at intervals by a control shaft actuating device to be described hereinafter. The operation of the pawls

142, 168 (see Fig. 2) is controlled by a selecting control disc 184 rockably mounted on the narrowing spindle 140 and connected through the medium of a Bowden wire 186 to another spring-loaded cam follower associated with another controlling cam keyed to the automatically actuated control shaft 182.

For a more detailed description of the carrier spindle drive and narrowing spindle drive, which may be of any suitable construction, reference is had to my copending U. S. patent application Serial No. 743,938 filed on April 25, 1947, now Patent No. 2,574,487, November 13, 1951, for a Straight Bar Knitting Machine.

The carrier spindle nuts control the strokes of reciprocable yarn carriers 188 carried by reciprocable carrier rods 190 in any suitable manner.

As best shown in Fig. 2, the pattern chain control jack 56n at the left-hand end of the row of jacks is connected by a wire 192 with the lower end of a lever 194, the upper end of which is secured to one end of a rod 196 journaled in suitable bearings of the frame of the machine. The other end of said rod 196 is connected with the lower end of a lever 198, the upper end of which is pivotally connected with one end of a wire 200 (see Figs. 1 and 4). The other end of said wire 200 is pivoted to an arm of a double-armed controlling element 202 swingably mounted at 204 on a block 206. Said block 206 being substantially of U-shaped cross-section is swingably mounted on the shaft 92 and carries an adjustable stop screw 208 capable of cooperation with the shaft 96 of the machine. A spring 210 (see Fig. 2) stretched between a downward extension 212 of said block 206 and a stationary point of the machine tends to urge said stop screw 208 (Fig. 4) against said shaft 96, whereby the block 206 is held in a substantially horizontal position. Furthermore, a double-armed spring-loaded follower 214 carrying a roller 216 cooperating with a control shaft cam 218 keyed to the main cam shaft 38 is swingably mounted on the shaft 92 between the side walls of the U-shaped block 206. During the operation of the machine, the arm 220 of the follower 214 may freely rock within the U-shaped block 206 as long as the controlling element 202 is in an inactive position, wherein its left-hand end (as viewed in Fig. 4) is out of the path of the arm 220. As soon as, however, said controlling element 202 is brought in response to an actuation of the jack 56n by a button on the pattern chain into the active position shown in Fig. 4, wherein its left-hand end is below the arm 220 of the cam follower 214, a rocking movement of the cam follower 214 causes a similar rocking movement of the block 206. As soon as the pattern chain controlled jack 56n causes a return of the controlling element 202 into its inactive position, the cam follower 214 will again freely rock without an actuation of the block 206 held in its substantially horizontal position by means of the spring 210.

As best shown in Figs. 2 and 4, one end of a connecting rod 222 is pivoted at 224 to the downward extension 212 of the block 206. The other end of said connecting rod 222 is pivoted at 226 to a lever 228 rockably mounted on the control shaft 182. Said lever 228 carries a pawl 230 arranged for engagement with teeth of a ratchet wheel 232 keyed to the rotatable control shaft 182. Apparently, each time the block 206 is rocked by the follower 214 upon a movement of the controlling element 202 into its active position in response to

the control by a button on the pattern chain, the ratchet wheel 232 and the control shaft 182 connected therewith are advanced one step by the pawl 230. Such a step-by-step movement of the control shaft 182 causes a step-by-step movement of the controlling cams mounted on the control shaft 182, such as the controlling cam 180 and others to be mentioned hereinafter, for the control of a mechanism or mechanisms of the knitting machine.

Referring now to Figs. 1, 5 and 10, two narrowing machine cams 234 are keyed to the main cam shaft 38. In a manner known per se, each narrowing machine cam 234 is composed of a round disc 236, and an element 238 being in the shape of a cam. During the normal knitting operations of the knitting machine, rollers 240 carried by spring-loaded cam followers 242 swingably mounted on the shaft 96 are in engagement with the round discs 236, so that, during the normal knitting operations no movement is imparted to said cam followers 242. However, at certain predetermined intervals, for example during the performance of a narrowing operation, the main cam shaft 38 is shifted to the right by an automatic shifting mechanism known per se, and not shown in the drawings, whereby the rollers 240 are brought into engagement with the cams 238 so that the cam followers 242 are rocked about the shaft 244 in accordance with the shape of the cams 238. The lower end of a connecting rod 246 is pivoted at 248 to each of said cam followers 242. As best shown in Figs. 5 and 10, the upper end of each connecting rod 246 is swingably connected with a narrowing machine tube 250 forming a part of the so-called narrowing machine generally indicated by 252. Said narrowing machine 252 comprises two arms 254 secured to a narrowing machine shaft 256 (see Figs. 5, 6, 8, 10 and 16) by means of set screws 258. The narrowing machine shaft 256 is journaled in suitable bearings of the frame of the machine. As best shown in Fig. 10, one end of a plate-like member 260 is adjustably secured to each arm 254 of the narrowing machine 252; the other end of each member 260 is secured to the narrowing machine tube 250 by a set screw 262. Thus, when the cam followers 242 are rocked by the cams 238 about the shaft 244, the narrowing machine arms 254 as well as the narrowing machine tube 250 are lowered and lifted causing at the same time a corresponding rotation of the narrowing machine shaft 256 in clock-wise and counter-clock-wise direction.

As best shown in Figs. 1, 5, 6, and 10, six brackets 264 are rigidly secured to the narrowing machine tube 250, for example by set screws 266. The outer brackets at the left-hand end and right-hand end of the machine are provided with two recesses 268 and 270. The four inner brackets 264 (see Figs. 1, 6, 10, 11, 11A and 12) are provided with three recesses 268, 270 and 272 and a bearing 273. An upper rail 274 is slidably engaged with the recesses 268 of the series of brackets 264. A lower rail 276 is slidably engaged with the recesses 270 of the series of brackets 264. An abutting bar 278 is immovably connected with the recesses 272 of the inner brackets 264. In each section of the machine, a right-hand narrowing finger 280R is rigidly connected with the reciprocable upper rail 274 and a left-hand narrowing finger 280L is rigidly connected with the lower reciprocable rail 276 by screws. Furthermore, as best shown in Fig. 1, an abutment 282 rigidly secured to the right-hand end of the upper recip-

reciprocable rail 274 is held in a manner known per se by means of a spring (not shown) in loose engagement with a downward extension 284R of the right-hand narrowing spindle nut 146R threaded on the narrowing spindle 140 and guided by a guiding rod 286 secured to the frame of the machine and engaged with a recess 283R (Figs. 1 and 5) of the narrowing spindle nut 146R. In a similar manner an abutment 298 secured to the lower reciprocable rail 276 is held by means of a spring (not shown) in loose engagement with a downward extension 284L of the left-hand narrowing spindle nut 146L threaded on the narrowing spindle 140 and guided by the guiding rod 286 engaged with a recess 283L of the narrowing spindle nut 146L.

Fig. 1 illustrates the narrowing spindle nuts 146L and 146R in their outermost position and the narrowing fingers 280L, 280R in a corresponding position outside the knitting field of each section containing a series of needles 292 and a series of sinkers 294. Apparently, above described forward-racking of the narrowing spindle nuts 146 or movement thereof towards each other caused by an actuation of the narrowing spindle drive results in a movement of the narrowing fingers 280L and 280R secured to the rails 276 and 274 towards each other into the knitting field. On the other hand a back-racking of the narrowing spindle nuts 146L, 146R or movement thereof away from each other from an inner position into their outermost position results in a movement of the narrowing fingers 280L, 280R from a position within the knitting field into the position outside the knitting field.

Referring now to Figs. 1, 5, 6, 11, 11A, 12, 14, and 16-19, a rod 296 is rotatably and axially movably arranged in the bearings 273 of the inner brackets 264 secured to the narrowing machine tube 250. In each section of the machine, a picot bar 298 is rigidly secured to said rod 296 by screws or the like. During the normal knitting operations of the machine, said picot bar 298 is in the upward position shown in Figs. 1, 5, 6, 11, 11A, 12, and 16, wherein its picot points 300 are out of cooperative relation to the needles 292 of the machine. Apparently, the picot bars 298 secured to the rod 296 journaled in bearings of the brackets 264 secured to the narrowing machine tube 250 participate in the downward and upward movements of the narrowing machine caused by above described narrowing machine actuating mechanism. However, as long as the picot points 300 are in the upward position out of cooperative relation to the needles 292 as shown, for example, in Fig. 1, such a downward and upward movement of the narrowing machine 252 will not cause an operation by the picot points.

According to the invention, the picot bars 298 with their picot points 300 may be swung automatically at predetermined intervals from the upward position out of cooperative relation to the needles of the machine as shown, for example, in Figs. 1 and 16 into a downward position in cooperative relation to the needles of the machine as shown, for example, in Fig. 17 and may be automatically returned from said downward position into said upward position by means of the following mechanism:

As best shown in Fig. 5, a control cam 302 keyed to the above described control shaft 182 cooperates with a spring-loaded cam follower 304 swingably mounted on the shaft 178. An arm of said cam follower 304 is pivotally connected at 306 with the lower end of a wire or rod 308, the

upper end of which is pivoted at 310 to a projection 312 of a camming element 314 swingably but axially immovably mounted on the narrowing machine shaft 256 (see Figs. 5, 6, 8, 9, and 16). The camming element 314 has a path 316 slidably engaged with a roller 318 carried by an arm 320 of a double-armed lever 322 swingably but axially immovably mounted on a stud 324 rigidly secured to a bracket 326 which, in turn, is rigidly connected with the narrowing machine shaft 256, so as to participate in the rocking movements of the latter. The upwardly extending arm 328 or "driver" of the double-armed lever 322 is provided with a bore 330 (see Figs. 6 and 16) slidably engaged with a rod 332. A set collar 334 secured to the rod 332 is arranged for abutting cooperation with the upper end of the arm 328. Furthermore, a collar 336 also arranged for abutting cooperation with said upper end of the arm 328 is slidably mounted on said rod 332. A spring 338 is interposed between said movable collar 336 and a set collar 342 secured to the rod 332. Therefore, if the arm 328 is moved in counter-clock-wise direction from the position shown in Fig. 6 into the position shown in Fig. 16, the rod 332 will be shifted to the left, if there is no obstacle preventing the rod 332 from movement. If, however, there is an obstacle, a movement of the arm 328 in counter-clock-wise direction will merely cause a compression of the spring 338. On the other hand, a movement of the arm 328 in clock-wise direction from the position shown in Fig. 16 into the position shown in Fig. 6 will cause a displacement of the rod 332 to the right. The right-hand end of the rod 332 is pivoted at 342 to an arm 344 of a bell-crank lever 346 swingably but axially immovably mounted on a stud 348 carried by a bracket 350 secured to the narrowing machine tube 250 by a screw 352 (see Figs. 6, 11A, 12, 14, 16 and 19).

The arm 354 of the rockable bell-crank lever 346 is pivotally connected at 356 with one end of a rod 358, the other end of which is pivotally connected at 360 with a projection 362 of a selecting control disc or conditioning means 364 swingably mounted on the rod 296 carrying the picot bars 298. As best shown in Figs. 15-19, said selecting control disc has two circular elevated portions 366, 368, and two recesses 370, 372, as well as a safety abutment 373 projecting from the recessed portion of the control disc. The elevated portion 366 and recessed portion 370 cooperate with a spring-loaded lifting pawl 374 mounted on an arm 376 of an actuating element 378 swingably arranged on the rod 296 carrying the picot bars 298. The elevated portion 368 and recessed portion 372 of the control disc 364 cooperate with a spring-loaded lowering pawl 380 arranged on an arm 382 of said rockable actuating element 378. The lifting pawl 374, in turn, is arranged for cooperation with teeth of a lifting ratchet wheel 384 keyed to said rod 296 carrying the picot bars 298; said lowering pawl 380 is arranged for cooperation with teeth of a lowering ratchet wheel 386 likewise keyed to said rod 296. When the selecting control disc or conditioning means 364 is in such a position, that the lifting pawl 374 is in engagement with the elevated portion 366 thereof as shown, for example, in Figs. 16 and 17, the lifting pawl 374 is held in an inactive position out of engagement with the teeth of the lifting ratchet wheel 384; on the other hand, when the selecting control disc or conditioning means 364 is in such a position, that the elevated portion 368 is in engagement

with the lowering pawl 380 as shown, for example, in Fig. 19, the lowering pawl 380 is held in an inactive position out of engagement with the teeth of the lowering ratchet wheel 386. The lifting ratchet wheel 384 has its series of teeth only at a portion of its circumference; likewise, the lowering ratchet wheel 386 has its series of teeth only at a portion of its circumference. The safety abutment 373 of the selecting control disc may cooperate with a safety locking shoulder 388 arranged on the reciprocable lower rail 270 carrying the narrowing fingers 280L. As best shown in Figs. 11, 11a, 12, the safety locking shoulder 388 extends along a certain length of the lower rail 276. When the narrowing fingers 280L, 280R are out of the knitting field as shown in Figs. 1, 11, 11a, and 12, the right-hand end of the safety locking shoulder 388 is out of the path of the safety abutment 373 of the selecting control disc 364 (see Fig. 12), so that the selecting control disc 364 may be freely rocked. If, however, the rails 274 and 276 carrying the narrowing fingers 280R and 280L are displaced by the narrowing spindle nuts 146R and 146L, so that the narrowing fingers are in the knitting field and the lower rail 276 provided with the safety shoulder 388 is shifted to the right as viewed in Figs. 1, 11, and 12, the shoulder 388 will be in the path of the abutment 373 of the selecting control disc 364, so that the latter is locked and cannot be rocked.

As best shown in Fig. 9, the path 316 of the camming element 314 is composed of a first circular section 390, having the center C of the narrowing machine shaft 256 as its center, a camming section 392 and a second circular section 394 likewise having the center C of the narrowing machine shaft 256 as its center. Therefore, when the camming element 314 is either in the position shown in Figs. 6 and 9 or in the position shown in Fig. 16 and when the narrowing machine 252 performs its lowering and lifting movements around the center C of the narrowing machine shaft 256 for performing narrowing operations by the narrowing fingers, which lowering and lifting movements result in a rocking of the bracket 326 and stud 324 carrying the lever 322 around the center C of the narrowing machine shaft 256, the roller 318 carried by the lever 322 will merely slide along the circular path section 390 or 394 without causing a relative movement between the lever 322 and the bracket 326. In other words, such downward and upward movements of the narrowing machine 252 for the performance of narrowing operations will not cause a displacement of the selecting control disc 364 connected to said lever 322 through the medium of the linkage 332, 346, 358. If, however, the controlling cam 302 (Fig. 5) causes a rocking of the camming element 314 from the position shown in Figs. 5, 6 and 9 into the position shown in Fig. 16, the camming section 392 cooperating with the roller 318 of the lever 322 will cause a rocking movement of the lever 322 about the stud 324 relative to the bracket 326 from the position shown in Fig. 6 into the position shown in Fig. 16, whereby the selecting control disc 364 is rocked from the position shown in Fig. 6 into the position shown in Fig. 16 through the medium of the linkage 332, 346, 358 connecting the lever 322 with said control disc 364; likewise, when the camming element 314 is swung from the position shown in Fig. 16 into the position shown in Fig. 6, the selecting control disc 364 will be swung from the position shown in Fig. 16 into the position shown in Fig. 6.

Referring now to Figs. 1-3 and 5-7, the pattern-chain controlled jack 56e is rigidly connected with a wire 386 passing through a bore at its upper end. The right-hand end of said wire 386 (as viewed in Fig. 1) is pivotally connected with the lower end of a lever 398, the upper end of which is connected to one end of a rod 400 (see Figs. 1, 5 and 6) journalled in suitable bearings of the frame of the machine. The other end of said rockable rod 400 is rigidly connected with the lower end of an arm 402, the upper end of which is connected to a wire 404, which, in turn, is connected to one arm of a controlling element 406 swingably mounted on a pin 408 (Fig. 7) projecting from the base of a spring-loaded block 410 swingably mounted on the shaft 92. A spring-loaded follower 412 swingably mounted on the shaft 92 and actuated by a pivot bar cam 414 may cause rocking movements of said block 410 when the pattern chain controlling element 406 is in such a position, that it is in the path of the arm 416 of the cam follower 412. On the other hand, when said controlling element 416 is in the position shown in Fig. 7, the cam follower 412 will freely rock within the U-shaped block 410 without causing an actuation thereof (the control and operation of the block 410 is the same as described above in connection with the blocks 90 and 206).

As best shown in Figs. 5-7, the projecting end of an arm 418 rigidly connected with the block 410 is pivotally connected at 420 with the lower end of a rod 422, the upper end of which is pivotally connected at 424 (see Figs. 8 and 16) to a projection 426 of a camming element 428 swingably and axially immovably mounted on the narrowing machine shaft 256. The camming element 428 is of the same design as above described camming element 314 and its path 430 is likewise composed of two circular sections and a central camming section. The path 430 of the camming element 428 is slidably engaged with a roller 432 carried by the arm 434 of a double-armed lever 436 swingably mounted on the stud 324 carried by the bracket 326 rigidly connected with the narrowing machine shaft 256. The upper end of an arm or "driver" 438 of the double-armed lever 436 is provided with a bore receiving one end portion of a rod 440. Said collars 442 and 444 (see Fig. 16) secured to said rod 440 are in abutting engagement with the upper end of the arm 438, so that a rocking movement of the lever 436 results in a positive displacement of the rod 440. The other end of said rod 440 is pivotally connected at 446 with an arm 448 of a bell-crank lever 450 swingably mounted on the stud 348 carried by the bracket 350 secured to the narrowing machine tube 252. An arm 452 of the bell-crank lever 354 is pivotally connected at 454 with one end of a rod 456, the other end of which is pivoted at 458 to an arm 460 of the actuating element 378 carrying the pawls 374, 380.

Thus, when the narrowing machine 252 performs downward and upward movements for the performance of narrowing operations by the narrowing fingers, the double-armed lever 436 will not be moved relatively to the bracket 326 owing to the circular section of the path 430 of the camming element 428, be it in the position shown in Fig. 16 or be it in a position corresponding to the position of the camming element 314 shown in said Fig. 16. However, if, upon an actuation of the rockable block 410 in response to a displacement of the controlling element 406 caused by the associated controlling cam of the control shaft,

the block 410 is rocked by means of the cam follower 412 from the position shown in full lines in Fig. 6 into the position shown in dash and dot lines in said Fig. 6 and vice versa, a corresponding reciprocating rocking movement of the camming element 428 will cause a rocking of the double-armed lever 436 relative to the bracket 326 and, consequently, through the medium of the linkage 440, 450, 456, a corresponding rocking of the actuating element 378 from the position shown in Figs. 6 and 16 into the position shown in Fig. 18 and vice versa. Such a reciprocating rocking movement of the actuating element 378, in turn, will cause a step-by-step rotation of the lowering ratchet wheel 386 and the rod 296 carrying the picot bars 298 when the selecting control disc or conditioning means 364 is in such a position, that the lowering pawl 388 may engage teeth of the lowering ratchet wheel 386; apparently, such an intermittent rotation of the rod 296 by the lowering pawl 388 cooperating with the lowering ratchet wheel 386 may bring the picot bars 298 from the position shown in Fig. 6, i. e. the position out of cooperative relation to the needles 292 into the position shown in Fig. 19, i. e. the position in cooperative relation to the needles 292. On the other hand, if the selecting control disc or conditioning means 364 is in such a position that the lifting pawl 374 may cooperate with teeth of the lifting ratchet wheel 384, such a reciprocating rocking movement of the actuating element 378 will cause a step-by-step upward swinging of the picot bars 298 from the position shown in Fig. 19 into the position shown in Fig. 6. Obviously, depending on its position, the selecting control disc 364 conditions the actuating drive of the picot bars 298 either for a downward or upward movement of the latter.

As best shown in Figs. 11a, 12 and 13, the rod 296 and the picot bars 298 carried by said rod 296 may be held in any position by means of a spring loaded detent 462 swingably mounted on a pin 464 carried by the bracket 350. Said spring-loaded detent 462 is arranged for engagement with teeth of an index wheel 466 rigidly secured to the rod 296 by a screw 468. As may be gathered from Figs. 17-19, the picot bars 298 abut in their lowermost position against the abutting rail 278 carried by the brackets 264, so that they are held in their proper position for a proper cooperation of their points 300 with the needles 292.

As best shown in Figs. 11a, 12, 14, 15, 17, 18 and 19, the rockable actuating element 378 is provided with an arm 470 having a threaded bore for receiving the threaded shaft of an adjustable shifting button 472. Furthermore, the threaded shaft of an abutting button 474 is screwed into a threaded bore of the bracket 350. The abutting button 474 is substantially in alignment with the pin carrying the lifting pawl 374 without contacting same when the actuating element 378 is in the position shown in Figs. 6, 11a, 12, 16 and 17. However, as may be gathered from Figs. 11a and 12, the abutting button 474 projects into the path of the shifting button 472 when the latter is rocked during a rocking of the actuating element 378. As long as the arm 470 of the actuating element 378 is in the position shown in Figs. 6, 11a, 12, 16 and 17, for example, the abutting button 474 does not interfere with the shifting button 472. If, however, the arm 470 is moved from the position shown in Figs. 6, 11a, 12, 16 and 17, into the position shown in Figs. 14, 18, and 19, the abutting button 474 and shifting button 472 come into engagement with

each other, and are in alignment with each other, when the actuating element 378 reaches its extreme position shown in said Figs. 14, 18, and 19. As may be gathered from Figs. 11a, 12, and 14, the actuating element 378 is rotatably mounted on the rod 296 between set collars 476 and 480 rigidly secured to said rod 296 by screws 482 and 484 respectively. Furthermore, a spring 478 is interposed between a bracket 264 and the ratchet wheel 384 keyed to the rod 296. Therefore, such a sidewise shifting of the actuating element 378 from the position shown in Fig. 11a into the position shown in Fig. 14 by the action of the cooperating abutting button 474 and shifting button 472 causes a similar sidewise shifting of the rod 296 in the direction of its longitudinal axis and a similar sidewise shifting of the ratchet wheels 384, 386 and selecting control disc 364 against the action of the spring 478. As may be gathered by a comparison of Fig. 11a with Fig. 14, such a sidewise shifting of the rod 296 causes a sidewise shifting of the points 300 of the picot bars 298 to the left through a distance equal to the distance between adjacent needles 292 of the knitting machine; in other words, the cooperating abutting button 474 and shifting button 472 cause a displacement of the picot bars 298 one needle to the left. When the rockable actuating element 378 is returned by its actuating drive from the position shown in Figs. 14, 18, and 19, into the position shown in Figs. 6, 11a, 12, 16, and 17, the spring 478 causes automatically a return displacement to the right of the picot bars 298, rod 296, ratchet wheels 384, 386, selecting control disc 364 and actuating element 378 into the position shown in Figs. 11a and 12, wherein the set collar 480 abuts against the bracket 350.

Referring now to Figs. 1 and 3, the left-hand end of the wire 396 connected to the jack 56c passes through a bore 486 of an arm 488 of a bell-crank lever 490 swingably mounted at 492 on a bracket 494 secured to the shaft 178. Above described hook-like locking element 76 constitutes the other arm of said bell-crank lever 490. A positive connection of said bell-crank lever 490 with the wire 396 is assured by means of said collars 496 rigidly secured to the wire 396 for abutting cooperation with the lower end of the arm 488 of the bell-crank lever 490. As long as the jack 56c is in the inactive position shown in full lines in Fig. 3, the bell-crank lever 490 is likewise in an inactive position shown in full lines in Fig. 3, wherein its hook-like locking element 76 is out of the path of the hook-like projection 74 of the lever 62, so that the jack 56c may cause a rocking of the lever 62 from the dash and dot line position shown in Fig. 3 into the full-line position shown in Fig. 3 with the result of an actuation of the narrowing spindle for a displacement of the narrowing fingers in the manner described above. If however, the jack 56c is rocked into an active position by means of a button 42 on the pattern chain 40, the bell-crank lever 490 is swung into the dash and dot-line position shown in Fig. 3, wherein its hook-like locking element 76 is in locking engagement with the hook-like projection 74 of the lever 62, so that the latter cannot be swung about its pivot 64 when by inadvertence a button of the pattern chain should cause a rocking of the jack 56c. In other words, the bell-crank lever 490 constitutes a safety device preventing an actuation of the narrowing spindle and displacement of the narrowing fingers when the rockable actuating element 378 is actuated in response to a rocking of the pattern chain control

jack 58e for a lowering or lifting of the picot bars 298. Thus, an inadvertent moving of the narrowing fingers 280L, 280R into the knitting field during an operation of the picot bars 298 is eliminated.

During the normal knitting operations and during the performance of narrowing operations, the picot bars 298 are in their upwardly-turned position shown in Figs. 1, 6, 11, 11a, and 12. Furthermore, the selecting control disc 364 is in the position shown in Fig. 6, wherein it holds the lowering pawl 380 out of engagement with teeth of the associated lowering ratchet wheel 386. The lifting pawl 374 is in such a relation to the lifting ratchet wheel 384, that it does not find a tooth thereof, when the actuating element 378 should be swung in counterclockwise direction as viewed in Fig. 6. Therefore, if, during such normal knitting operations and/or narrowing operations the actuating element 378 should be rocked by its actuating drive, it will have no influence on the position of the picot bars 298, as the lowering pawl 380 is held out of engagement with teeth of its associated ratchet wheel and the lifting pawl 374 cannot find a tooth of its associated ratchet wheel for causing a rotation thereof. Furthermore, as shown in Fig. 6, when the selecting control disc 364 is in the set position, the safety abutment 373 arranged thereon is in a position above the plane of the safety locking shoulder 388 of the lower reciprocable rail 276 carrying the narrowing fingers 280L. As mentioned above, as long as the narrowing fingers 280L, 280R are in the knitting field, the safety locking shoulder 278 is in the path of the safety abutment 373 of the selecting control disc, so that the latter cannot be turned. Therefore, if, owing to an improper arrangement of the controls of the knitting machine, the controlling cam 302 (Fig. 5) should cause a rocking of the camming element 314 at a time, when the narrowing fingers 280L, 280R are still in the knitting fields, the thus resulting rocking of the double-armed lever 322 will merely cause a compression of the spring 338 without a rocking of the selecting control disc 364 locked by the cooperating safety abutment 373 and safety locking shoulder 388; if, further, at such improper interval, the controlling element 406 (Figs. 5 and 6) should cause an actuation of the block 410 with the result of a rocking of the actuating element 378, the pawls 374 and 388 will be idle and will not cause a movement of the picot bars 298. In other words, the safety device 373, 388 prevents an inadvertent actuation of the picot bars 298, as long as the narrowing fingers 280L, 280R are within the knitting fields and would be in the way of the picot bars, if the latter would be swung downwardly.

Now, assume the picot bars are not prevented from operation, the operation of the knitting machine during an actuation of the picot bars is as follows:

The narrowing fingers 280L, 280R are without the knitting field as shown in Figs. 1, 11, 11a, and 12. Furthermore, prior to the actuation of the picot bars 298, the latter are in their upward position out of cooperative relation to the needles 292 of the knitting machine as shown in the same figures and in Figs. 5, 6, and 16.

At a predetermined interval during the knitting of the welt the selecting control disc 364 is brought by means of the controlling cam 302 and the linkage 304, 308, 314, 322, 332, 346, 358 (Fig. 5) from the position shown in Fig. 6 into the

position shown in Fig. 16, whereby the lowering pawl 380 is rendered effective. As soon as the controlling element 406 (Figs. 5-7) is brought into an active position in response to an actuation of the jack 58e by the pattern chain 40, the block 410 is rocked back and forth by its actuating drive 412, 414 during each revolution of the main cam shaft 38. Such a rocking movement of the block 410 results in a similar rocking movement of the actuating element 378 carrying the lifting pawl 374 and the lowering pawl 380 through the medium of the linkage 422, 428, 436, 440, 450, 456. Owing to above mentioned automatic setting of the selecting control disc 364 in the position shown in Fig. 16, the lifting pawl 374 is rendered ineffective, while the lowering pawl 380 may come into engagement with a tooth of the lowering ratchet wheel 386, when, after a rocking of the actuating element 378 in counter-clockwise direction, the latter is returned into its starting position in clockwise direction. Thus, as long as the controlling element 406 is in its active position, the rod 296 rigidly connected with the lowering ratchet wheel 386 and with the picot bars 298 will be rotated one step in clockwise direction during each revolution of the main cam shaft. Thus, the picot bars 298 are swung automatically step by step from their upward position out of cooperative relation to the knitting needles 292 of the knitting machine as shown in Fig. 16 into their downward position in cooperative relation to the knitting needles of the knitting machine as shown in Fig. 17. In said downward position of the picot bars 298 the latter rest against the abutting bar 278, and the lowering pawl 380 is in engagement with the last tooth out of a series of nine teeth of the lowering ratchet wheel 386. Therefore, any further rocking of the actuating element 378 while the selecting control disc 364 is still in the position shown in Fig. 17 cannot cause any further rotation of the rod 296 and picot bars 298 in clockwise direction.

Now, at a predetermined interval, the pattern chain causes in a manner known per se a displacement to the right of the main cam shaft 38, so that the cams 238 of the narrowing machine cam 252 come into engagement with the rollers 240 of the cam followers 242 of the narrowing machine actuating drive. The cams 238 are shaped in such a manner, that during one revolution of the main cam shaft 38, the narrowing machine 252 at first is dipped from its normal extreme uppermost position into an extreme lowermost position, whereupon it is lifted to a certain extent into an intermediate position, whereupon it is dipped again into its extreme lowermost position and whereupon it is lifted into its normal extreme uppermost position.

Prior to and during above mentioned first dipping of the narrowing machine 252 into its extreme lowermost position, the picot bars 298 and the actuating element 378 are in the position shown in Fig. 17, so that, during said dipping, the points 300 of the picot bars 298 may come into engagement with every second needle of the series of needles 292 of the knitting machine as may be gathered from Figs. 11, 11a, and 14 for picking up loops of the fabric. Now, when the narrowing machine 252 is lifted into its intermediate position, and before the narrowing machine reaches again its extreme lowermost position during the second dipping thereof during a revolution of the main cam shaft, the actuating element 378 is swung from the position shown in

Fig. 17 into the position shown in Fig. 18, while the selecting control disc 364 remains in its position. During said rocking movement of the actuating element 378 into the position shown in Fig. 18, the shifting button 472 carried by the arm 470 of the actuating element 378 comes into engagement with the abutting button 474 as shown in Figs. 14 and 18, whereby, in the manner described above, the points 300 of the picot bars 298 are shifted one needle to the left. During 10 said second dipping of the narrowing machine 252 from its intermediate position into its extreme lower-most position, the points 300 of the picot bars 298 are held in the position shown in Fig. 14 by the shifting button 472 and abutting button 474 remaining in engagement with each other during said time interval. Said second dipping of the narrowing machine 252 causes a transfer of the loops of the fabric one needle to the left as required for the manufacture of the picot.

After the completion of the loop transfer for the manufacture of the picot, the narrowing machine 252 is returned into its normal extreme uppermost position and the main cam shaft is likewise returned into its normal position, wherein the round discs 236 are in engagement with the rollers 240 of the cam followers 242, so that the narrowing machine remains in its extreme uppermost position during subsequent knitting operations until, in a manner known per se, the narrowing machine is again actuated for the performance of narrowing operations or other loop transfer operations.

Furthermore, as shown in Fig. 19, the selecting control disc 364 is automatically returned by means of the controlling cam 302 (Fig. 5) into its starting position, wherein it renders ineffective the lowering pawl 380 and permits an engagement of the lifting pawl 374 with teeth of the lifting ratchet wheel 384 when the actuating element 378 is rocked by its actuating drive. When the controlling disc 364 is set in the position shown in Fig. 19, and the actuating element 378 is rocked, the rod 296 rigidly connected with the lifting ratchet wheel 384 and the picot bars 298 will be rotated step by step (one step during each revolution of the main cam shaft) until the picot bars 298 reach their starting position shown in Fig. 6. The picot bars 298 cannot be swung farther, as in said position the lifting pawl 374 will not find any further tooth of the lifting ratchet wheel 384 during further rocking of the actuating element 378. There are only nine teeth on a portion of the circumference of the lifting ratchet wheel 384. Of course, as soon as the controlling element 406 (Figs. 5-7) is returned into its inactive position by a return of the jack 56e into its normal position, the rocking of the actuating element 378 is stopped and the latter remains in the position shown in Fig. 6.

I have described preferred embodiments of my invention, but it is understood that numerous changes and omissions may be made without departing from the spirit and scope of the invention set forth in the appended claims.

For example, the invention may also be applied to a straight bar knitting machine having more than two sections.

Furthermore, the invention may also be applied to loop transfer means of a knitting machine other than picot bars. For example, so-called lace-fingers may be automatically actuated by a mechanism according to the invention.

Moreover, the mechanism for the sidewise shifting of the loop transfer means must not necessarily be incorporated in the mechanism for moving the loop transfer means from a position out of cooperative relation to the knitting needles of the machine into a position in cooperative relation to the knitting needles of the machine and vice versa. If desired, a separate mechanism may be used for such a sidewise shifting. In the case of the application of the invention to lace-fingers, for example, the sidewise shifting of the lace-fingers through one needle or more than one needle may be carried out by a well-known lace-finger shifting apparatus.

Moreover, mechanisms according to the invention may be applied on the same machine to several loop transfer means, for example to picot bars as well as to lace-fingers.

Furthermore, if desired, it is possible to have a greater or smaller number than nine teeth on the circumference of the lifting and lowering ratchet wheels 384, 386, but of course, a portion of the circumference of said lifting and lowering ratchet wheels should remain free from teeth.

What I claim is:

1. A straight bar knitting machine, comprising: loop transfer means for transferring loops from needle to needle of the knitting machine during the operation thereof, said loop transfer means being swingably mounted on the knitting machine and being normally in a position out of cooperative relation to needles of the knitting machine, and an automatic transfer means actuating drive associated with said loop transfer means for swinging same step by step into and out of cooperative relation to needles of the knitting machine at predetermined intervals.

2. A straight bar knitting machine, comprising: loop transfer means for transferring loops from needle to needle of the knitting machine during the operation thereof, said loop transfer means being swingably mounted on the knitting machine and being normally in a position out of cooperative relation to needles of the knitting machine, and an automatic transfer means actuating drive associated with said loop transfer means for swinging same into and out of cooperative relation to needles of the knitting machine at predetermined intervals, said automatic transfer means actuating drive including means for performing said swinging of the loop transfer means into said cooperative relation during a plurality of revolutions of the main cam shaft of the knitting machine and for performing the return swinging of said loop transfer means from said cooperative relation into the position out of cooperative relation during a plurality of revolutions of the main cam shaft of the knitting machine.

3. A straight bar knitting machine, comprising: loop transfer means for transferring loops from needle to needle of the knitting machine during the operation thereof, said loop transfer means being swingably mounted on the knitting machine and being normally in a position out of cooperative relation to needles of the knitting machine, and an automatic transfer means actuating drive associated with said loop transfer means for swinging same into and out of cooperative relation to needles of the knitting machine at predetermined intervals, said automatic transfer means actuating drive including means for performing said swinging of the loop transfer means step by step into or out of said coopera-

tive relation during a plurality of revolutions of the main cam shaft of the knitting machine.

4. A straight bar knitting machine, comprising: loop transfer means for transferring loops from needle to needle of the knitting machine during the operation thereof, said loop transfer means being swingably mounted on the knitting machine and being normally in a position out of cooperative relation to needles of the knitting machine, a transfer means actuating drive associated with said loop transfer means, said transfer means actuating drive including an actuating mechanism associated with said loop transfer means for swinging same and including conditioning means cooperating with said actuating mechanism for conditioning the latter for a downward swinging of said loop transfer means into or for an upward swinging of said loop transfer means out of cooperative relation to needles of the knitting machine, automatic selecting means associated with said conditioning means for adjusting same at predetermined intervals so as to condition the actuating mechanism for a downward swinging or an upward swinging of the loop transfer means, and automatic controlling means associated with said actuating mechanism for rendering same active at predetermined intervals.

5. In a straight bar knitting machine as claimed in claim 4, said actuating mechanism including means for a step by step swinging of the loop transfer means.

6. In a straight bar knitting machine as claimed in claim 4, said automatic controlling means being set for rendering said actuating mechanism active during a plurality of revolutions of the main cam shaft.

7. In a straight bar knitting machine as claimed in claim 4, said actuating mechanism including means for a step by step swinging of the loop transfer means, and said automatic controlling means being set for rendering said actuating mechanism active during a plurality of revolutions of the main cam shaft.

8. A straight bar knitting machine, comprising: loop transfer means for transferring loops from needle to needle of the knitting machine during the operation thereof, said loop transfer means being swingably mounted on the knitting machine and being displaceable longitudinally of the knitting machine, said loop transfer means being normally in a position out of cooperative relation to needles of the knitting machine, an automatic transfer means actuating drive associated with said loop transfer means for swinging same into and out of cooperative relation to needles of the knitting machine at predetermined intervals, and automatic shifting means associated with said loop transfer means for displacing same sidewise back and forth at predetermined intervals, said shifting means being actuated by said automatic transfer means actuating drive.

9. In a straight bar knitting machine as claimed in claim 8, said automatic transfer means actuating drive including a ratchet wheel mechanism having a reciprocable pawl carrier, said ratchet wheel mechanism being displaceable longitudinally of the knitting machine and being coupled with said loop transfer means, resilient means acting on said ratchet wheel mechanism, a fixed abutment arranged on the knitting machine, and a shifting element mounted on said reciprocable pawl carrier, said abutment being in the path of said shifting element when

the pawl carrier is rocked whereby the ratchet wheel mechanism and the loop transfer means are displaced sidewise against the action of said resilient means upon an abutting engagement of said shifting element and said abutment during a stroke of said pawl carrier.

10. A straight bar knitting machine, comprising: loop transfer means for transferring loops from needle to needle of the knitting machine during the operation thereof, said loop transfer means being swingably mounted on the knitting machine and being displaceable longitudinally of the knitting machine, said loop transfer means being normally in a position out of cooperative relation to needles of the knitting machine, a transfer means actuating drive associated with said loop transfer means, said transfer means actuating drive including an actuating mechanism associated with said loop transfer means for swinging same and including conditioning means cooperating with said actuating mechanism for conditioning the latter for a downward swinging of said loop transfer means into or for an upward swinging of said loop transfer means out of cooperative relation to needles of the knitting machine, automatic selecting means associated with said conditioning means for adjusting same at predetermined intervals so as to condition the actuating mechanism for a downward swinging or an upward swinging of the loop transfer means, and automatic controlling means associated with said actuating mechanism for rendering same active at predetermined intervals, and automatic shifting means associated with said loop transfer means for displacing same sidewise back and forth at predetermined intervals.

11. In a straight bar knitting machine as claimed in claim 10, said shifting means being actuated by said transfer means actuating drive.

12. In a straight bar knitting machine as claimed in claim 10, said actuating means including a ratchet wheel mechanism for a step by step swinging of the loop transfer means, and said shifting means being actuated by said ratchet wheel mechanism.

13. In a straight bar knitting machine as claimed in claim 10, said actuating means including a ratchet wheel mechanism having a reciprocable pawl carrier for a step by step swinging of the loop transfer means, said ratchet wheel mechanism being displaceable longitudinally of the knitting machine and being coupled with said loop transfer means, resilient means acting on said ratchet wheel mechanism, a fixed abutment arranged on the knitting machine, and a shifting element mounted on said reciprocable pawl carrier, said abutment being in the path of said shifting element when the pawl carrier is rocked whereby the ratchet wheel mechanism and the loop transfer means are displaced sidewise against the action of said resilient means upon an abutting engagement of said shifting element and said abutment during a stroke of said pawl carrier.

14. A straight bar knitting machine comprising: supporting means rockably mounted on the knitting machine, an automatic actuating drive associated with said supporting means for moving same towards and away from the needles of the knitting machine at predetermined intervals, loop transfer means for transferring loops from needle to needle of the knitting machine during the operation thereof, said loop transfer means being swingably mounted on said rockable supporting means and being normally in a position

out of cooperative relation to needles of the knitting machine, a transfer means actuating drive associated with said loop transfer means, said transfer means actuating drive including an actuating mechanism associated with said loop transfer means for swinging same and including conditioning means cooperating with said actuating mechanism for conditioning the latter for a downward swinging of said loop transfer means into or for an upward swinging of said loop transfer means out of cooperative relation to needles of the knitting machine, automatic selecting means associated with said conditioning means for adjusting same at predetermined intervals so as to condition the actuating mechanism for a downward swinging or an upward swinging of the loop transfer means, and automatic controlling means associated with said actuating mechanism for rendering same active at predetermined intervals.

15. A straight bar knitting machine comprising: supporting means rockably mounted on the knitting machine, an automatic actuating drive associated with said supporting means for moving same towards and away from the needles of the knitting machine at predetermined intervals, loop transfer means for transferring loops from needle to needle of the knitting machine during the operation thereof, said loop transfer means being swingably mounted on said rockable supporting means and being displaceable longitudinally of the knitting machine, said loop transfer means being normally in a position out of cooperative relation to needles of the knitting machine, a transfer means actuating drive associated with said loop transfer means, said transfer means actuating drive including an actuating mechanism associated with said loop transfer means for swinging same and including conditioning means cooperating with said actuating mechanism for conditioning the latter for a downward swinging of said loop transfer means into or for an upward swinging of said loop transfer means out of cooperative relation to needles of the knitting machine, automatic selecting means associated with said conditioning means for adjusting same at predetermined intervals so as to condition the actuating mechanism for a downward swinging or an upward swinging of the loop transfer means, automatic controlling means associated with said actuating mechanism for rendering same active at predetermined intervals, and automatic shifting means associated with said loop transfer means for displacing same sidewise back and forth at predetermined intervals.

16. In a straight bar knitting machine as claimed in claim 15, said shifting means being actuated by said transfer means actuating drive.

17. A straight bar knitting machine comprising: supporting means rockably mounted on the knitting machine, an automatic actuating drive associated with said supporting means for moving same towards and away from the needles of the knitting machine at predetermined intervals, loop transfer means for transferring loops from needle to needle of the knitting machine during the operation thereof, said loop transfer means being swingably mounted on said rockable supporting means and being displaceable longitudinally of the knitting machine, said loop transfer means being normally in a position out of cooperative relation to needles of the knitting machine, an automatic transfer means actuating drive associated with said loop transfer means

5 for swinging same into and out of cooperative relation to needles of the knitting machine at predetermined intervals, and automatic shifting means associated with said loop transfer means for displacing same sidewise back and forth at predetermined intervals, said shifting means being actuated by said automatic transfer means actuating drive.

18. A straight bar knitting machine comprising: a narrowing machine including narrowing fingers displaceable longitudinally of the machine towards and away from each other, said narrowing machine being rockably mounted on the knitting machine, an automatic narrowing machine drive associated with said narrowing machine for moving same towards and away from the needles of the knitting machine at predetermined intervals, an automatic narrowing finger drive associated with said narrowing fingers for moving same into and out of the knitting field at predetermined intervals, loop transfer means for transferring loops from needle to needle of the knitting machine during the operation thereof, said loop transfer means being swingably mounted on said rockable narrowing machine and being normally in a position out of cooperative relation to needles of the knitting machine, an automatic transfer means actuating drive associated with said loop transfer means for swinging same into and out of cooperative relation to needles of the knitting machine at predetermined intervals, said transfer means actuating drive including a ratchet wheel mechanism mounted on said narrowing machine and coupled with said loop transfer means, a link-work connected to said ratchet wheel mechanism, links of said link-work being swingable about points participating in movements of said narrowing machine, cam means arranged for cooperation with the driver of said link-work and rockably mounted on the knitting machine in coaxial alignment with the pivotal connection between the narrowing machine and the knitting machine, an actuating lever swingably mounted on the knitting machine, connecting means connecting said actuating lever with said cam means, and a drive capable of actuating said actuating lever, the camming surface of said rockable cam means being shaped for actuating the driver of said link-work upon an actuation of said actuating lever and being shaped for permitting a movement of the narrowing machine without a movement of the links of said link-work relative thereto when said actuating lever is at a standstill.

19. A straight bar knitting machine comprising: a narrowing machine including narrowing fingers displaceable longitudinally of the machine towards and away from each other, said narrowing machine being rockably mounted on the knitting machine, an automatic narrowing machine drive associated with said narrowing machine for moving same towards and away from the needles of the knitting machine at predetermined intervals, an automatic narrowing finger drive associated with said narrowing fingers for moving same into and out of the knitting field at predetermined intervals, loop transfer means for transferring loops from needle to needle of the knitting machine during the operation thereof, said loop transfer means being swingably mounted on said rockable narrowing machine and being normally in a position out of cooperative relation to needles of the knitting machine, a transfer means actuating drive asso-

ciated with said loop transfer means, said transfer means actuating drive including an actuating mechanism associated with said loop transfer means for swinging same and including conditioning means cooperating with said actuating mechanism for conditioning the latter for a downward swinging of said loop transfer means into or for an upward swinging of said loop transfer means out of cooperative relation to needles of the knitting machine, automatic selecting means associated with said conditioning means for adjusting same at predetermined intervals so as to condition the actuating mechanism for a downward swinging or an upward swinging of the loop transfer means, and automatic controlling means associated with said actuating mechanism for rendering same active at predetermined intervals.

20. In a straight bar knitting machine as claimed in claim 19, said transfer means actuating drive including a ratchet wheel mechanism mounted on said narrowing machine, said ratchet wheel mechanism having two ratchet wheels with teeth in opposite directions, each of said ratchet wheels being coupled with said loop transfer means, a rockable pawl carrier having a first pawl for cooperation with the first ratchet wheel and a second pawl for cooperation with the second ratchet wheel, and a movable selecting element cooperating with said two pawls for selectively rendering one of them active, a first link-work connected to said selecting element, links of said first link-work being swingable about points participating in movements of said narrowing machine, first cam means arranged for cooperation with the driver of said first link-work and rockably mounted on the knitting machine in coaxial alignment with the pivotal connection between the narrowing machine and the knitting machine, first automatic controlling means connected to said first cam means for rocking same from one extreme position into another extreme position at predetermined intervals, the camming surface of said first rockable cam means being shaped for actuating the driver of said first link-work during a movement from one position into the other one and being shaped for permitting a movement of the narrowing machine without a movement of the links of said first link-work relative thereto when said first cam means is at a standstill, a second link-work connected to said pawl carrier, links of said second link-work being swingable about points participating in movements of said narrowing machine, second cam means arranged for cooperation with the driver of said second link-work and rockably mounted on the knitting machine in coaxial alignment with the pivotal connection between the narrowing machine and the knitting machine, an actuating lever swingably mounted on the knitting machine, connecting means connecting said actuating lever with said second cam means, an actuating lever drive, and second automatic controlling means arranged for periodically coupling said actuating lever drive with said actuating lever so as to cause actuation thereof, the camming surface of said second rockable cam means being shaped for actuating the driver of said second link-work upon an actuation of said actuating lever and being shaped for permitting a movement of the narrowing machine without a movement of the links of said second link-work relative thereto when said actuating lever is at a standstill.

21. In a straight bar knitting machine as

claimed in claim 20, said loop transfer means being displaceable longitudinally of the knitting machine, and automatic shifting means associated with said loop transfer means for displacing same sidewise back and forth at predetermined intervals.

22. In a straight bar knitting machine as claimed in claim 21, said shifting means being actuated by said transfer means actuating drive.

23. In a straight bar knitting machine as claimed in claim 19, said loop transfer means being displaceable longitudinally of the knitting machine, said transfer means actuating drive including a ratchet wheel mechanism mounted on said narrowing machine, said ratchet wheel mechanism being displaceable longitudinally of the knitting machine, resilient means acting on said ratchet wheel mechanism, said ratchet wheel mechanism having two ratchet wheels with teeth in opposite directions, each of said ratchet wheels being coupled with said loop transfer means, a rockable pawl carrier having a first pawl for cooperation with the first ratchet wheel and a second pawl for cooperation with the second ratchet wheel, and a movable selecting element cooperating with said two pawls for selectively rendering one of them active, a first link-work connected to said selecting element, links of said first link-work being swingable about points participating in movements of said narrowing machine, first cam means arranged for cooperation with the driver of said first link-work and rockably mounted on the knitting machine in coaxial alignment with the pivotal connection between the narrowing machine and the knitting machine, first automatic controlling means connected to said first cam means for rocking same from one extreme position into another extreme position at predetermined intervals, the camming surface of said first rockable cam means being shaped for actuating the driver of said first link-work during a movement from one position into the other one and being shaped for permitting a movement of the narrowing machine without a movement of the links of said first link-work relative thereto when said first cam means is at a standstill, a second link-work connected to said pawl carrier, links of said second link-work being swingable about points participating in movements of said narrowing machine, second cam means arranged for cooperation with the driver of said second link-work and rockably mounted on the knitting machine in coaxial alignment with the pivotal connection between the narrowing machine and the knitting machine, an actuating lever swingably mounted on the knitting machine, connecting means connecting said actuating lever with said second cam means, an actuating lever drive, second automatic controlling means arranged for periodically coupling said actuating lever drive with said actuating lever so as to cause actuation thereof, the camming surface of said second rockable cam means being shaped for actuating the driver of said second link-work upon an actuation of said actuating lever and being shaped for permitting a movement of the narrowing machine without a movement of the links of said second link-work relative thereto when said actuating lever is at a standstill, a fixed abutment arranged on the knitting machine, and a shifting element mounted on said reciprocable pawl carrier, said abutment being in the path of said shifting element when the pawl carrier is rocked whereby the

23

ratchet wheel mechanism and the loop transfer means are displaced sidewise against the action of said resilient means upon an abutting engagement of said shifting element and said abutment during a stroke of said pawl carrier.

24. A straight bar knitting machine comprising: a narrowing machine including narrowing fingers displaceable longitudinally of the machine towards and away from each other, said narrowing machine being rockably mounted on the knitting machine, an automatic narrowing machine drive associated with said narrowing machine for moving same towards and away from the needles of the knitting machine at predetermined intervals, an automatic narrowing finger drive associated with said narrowing fingers for moving same into and out of the knitting field at predetermined intervals, loop transfer means for transferring loops from needle to needle of the knitting machine during the operation thereof, said loop transfer means being swingably mounted on said rockable narrowing machine and being normally in a position out of cooperative relation to needles of the knitting machine, an automatic transfer means actuating drive associated with said loop transfer means for swinging same into and out of cooperative relation to needles of the knitting machine at predetermined intervals, and a safety device responsive to an actuation of said automatic transfer means actuating drive, said safety device being associated with said narrowing finger drive for locking same during an actuation of said transfer means actuating drive.

25. In a straight bar knitting machine as claimed in claim 24, first movable automatic controlling means arranged for periodical movements from an inactive position into an active position so as to render active said transfer means actuating drive, and second movable automatic controlling means arranged for periodical movements from an inactive position into an active position so as to render active said narrowing finger drive, said first movable automatic controlling means being further arranged for locking said second movable automatic controlling means in its inactive position when the former is moved into its active position.

26. In a straight bar knitting machine as claimed in claim 24, first movable automatic controlling means arranged for periodical movements from an inactive position into an active position so as to render active said transfer means actuating drive, second movable automatic controlling means arranged for periodical movements from an inactive position into an active position so as to render active said narrowing finger drive, and a locking element positively coupled with said first movable automatic controlling means, said locking element being arranged for locking engagement with said second movable automatic controlling means when the first movable automatic controlling means is moved into its active position so as to hold said second movable automatic controlling means in its inactive position.

27. A straight bar knitting machine comprising: a narrowing machine including narrowing fingers displaceable longitudinally of the machine towards and away from each other, said narrowing machine being rockably mounted on the knitting machine, an automatic narrowing machine drive associated with said narrowing machine for moving same towards and away from the needles of the knitting machine

24

at predetermined intervals, an automatic narrowing finger drive associated with said narrowing fingers for moving same into and out of the knitting field at predetermined intervals, loop transfer means for transferring loops from needle to needle of the knitting machine during the operation thereof, said loop transfer means being swingably mounted on said rockable narrowing machine and being normally in a position out of cooperative relation to needles of the knitting machine, an automatic transfer means actuating drive associated with said loop transfer means for swinging same into and out of cooperative relation to needles of the knitting machine at predetermined intervals, and a safety mechanism responsive to the position of the narrowing fingers, said safety mechanism being associated with said transfer means actuating drive for rendering same ineffective when said narrowing fingers are in the knitting field.

28. In a straight bar knitting machine as claimed in claim 27, an adjustable controlling element in said transfer means actuating drive for rendering same effective and ineffective, and a locking element positively connected to a narrowing finger, said locking element being arranged for locking said adjustable controlling element in a position wherein it renders said transfer means actuating drive ineffective when said narrowing finger is in the knitting field.

29. In a straight bar knitting machine as claimed in claim 27, said transfer means actuating drive including a ratchet wheel mechanism mounted on said narrowing machine, said ratchet wheel mechanism having a ratchet wheel coupled with said loop transfer means, a rockable pawl carrier carrying a pawl for cooperation with said ratchet wheel, and a movable controlling element arranged for rendering ineffective said pawl in a first position and for rendering effective said pawl in a second position, first automatic controlling means associated with said pawl carrier for periodically rocking same, second automatic controlling means associated with said movable controlling element for displacing same at predetermined intervals, and a locking element positively connected to a narrowing finger, said locking element being in the path of said movable controlling element when the latter is in said first position and said narrowing finger is in the knitting field whereby the movable controlling element is prevented from displacement into said second position.

30. In a straight bar knitting machine as claimed in claim 29, said narrowing machine including a reciprocable rail carrying said narrowing finger, and an abutment arranged on said rail, said abutment being in the path of said movable controlling element when the latter is in the position rendering the pawl ineffective and said narrowing finger is in the knitting field.

31. In a straight bar knitting machine as claimed in claim 27, said transfer means actuating drive including a ratchet wheel mechanism mounted on said narrowing machine, said ratchet wheel mechanism having two ratchet wheels with teeth in opposite directions, each of said ratchet wheels being coupled with said loop transfer means, a rockable pawl carrier carrying a first pawl for cooperation with the first ratchet wheel and a second pawl for cooperation with the second ratchet wheel, and a movable selecting element arranged for cooperation with said pawls, said movable selecting element being displaceable from a first position wherein it renders ineffective

said first pawl and renders effective said second pawl into a second position wherein it renders ineffective said second pawl and renders effective said first pawl, first automatic controlling means associated with said pawl carrier for periodically rocking same, second automatic controlling means associated with said movable selecting element for displacing same at predetermined intervals, and a locking element positively connected to a narrowing finger, said locking element being in the path of said movable selecting element when the latter is in said first position and said narrowing finger is in the knitting field whereby the movable selecting element is prevented from displacement into said second position.

32. In a straight bar knitting machine as claimed in claim 31, said narrowing machine including a reciprocable rail carrying said narrowing finger, and an abutment arranged on said rail, said abutment being in the path of said movable selecting element when the latter is in said first position and said narrowing finger is in the knitting field.

33. A method for the operation of a straight bar knitting machine having movable loop transfer means, comprising the steps of automatically moving said loop transfer means from a position out of cooperative relation to needles of the knitting machine into a position in cooperative relation to needles of the knitting machine while knitting at the same time several loop courses, automatically actuating said loop transfer means for transferring loops from needle to needle of the knitting machine, and automatically returning said loop transfer means from said position in cooperative relation to needles of the knitting machine into said position out of cooperative relation to needles of the knitting machine while knitting at the same time several loop courses.

34. In a method as claimed in claim 33, where in said loop transfer means are moved step by step from one position into the other one.

35. A straight bar knitting machine, comprising loop transfer means for transferring loops from needle to needle of the knitting machine during the operation thereof, said loop transfer means being swingably mounted on the knitting machine and being normally in a position out of cooperative relation to needles of the knitting machine and an automatic transfer means actuating drive associated with said loop transfer means for swinging same step by step into and out of cooperative relation to needles of the knitting machine at predetermined intervals, said transfer means actuating drive including a ratchet wheel mechanism mounted on said knitting machine, said ratchet wheel mechanism having two ratchet wheels each being coupled with said loop transfer means, a rockable pawl

carrier carrying a first pawl for cooperation with the first ratchet wheel and a second pawl for cooperation with the second ratchet wheel and arranged for the drive of said ratchet wheels in opposite directions, and a movable selecting element arranged for cooperation with said pawls, said movable selecting element being displaceable from a first position wherein it renders ineffective said first pawl and renders effective said second pawl into a second position wherein it renders ineffective said second pawl and renders effective said first pawl, first automatic controlling means associated with said pawl carrier for periodically rocking the same, and second automatic controlling means associated with said movable selecting element for displacing same at predetermined intervals.

36. A straight bar knitting machine, comprising loop transfer means for transferring loops from needle to needle of the knitting machine during the operation thereof, said loop transfer means being swingably mounted on the knitting machine and being normally in a position out of cooperative relation to needles of the knitting machine, a transfer means actuating drive associated with said loop transfer means, said transfer means actuating drive including an actuating mechanism associated with said loop transfer means for swinging same and including conditioning means cooperating with said actuating mechanism for conditioning the latter for a downward swinging of said loop transfer means into or for an upward swinging of said loop transfer means out of cooperative relation to needles of the knitting machine, automatic selecting means associated with said conditioning means for adjusting same at predetermined intervals so as to condition the actuating mechanism for a downward swinging or an upward swinging of the loop transfer means.

37. In a straight bar knitting machine as claimed in claim 36, said actuating mechanism including means for a step by step swinging of the loop transfer means.

38. In a straight bar knitting machine as claimed in claim 36, said actuating mechanism including means for a step by step swinging of the loop transfer means during a plurality of revolutions of the main cam shaft.
